UNITED STATES PATENT OFFICE.

JOHN G. KOEGL, OF TOLEDO, OHIO, ASSIGNOR OF ONE-HALF TO HUGO BOELTER, OF TOLEDO, OHIO.

LADLE.

Application filed June 17, 1926. Serial No. 116,604.

My invention has for its object to provide an efficient means for manipulating or handling molten metals or other liquids. It particularly has for its object to provide a 5 ladle for molten metals that is so constructed that it may be readily filled and easily emptied. In constructions containing my invention molds used for casting metals may be filled without spilling and the metal taken from below the surface of the metal in the ladle and thus avoid the entry of oxidized metal or dross into the molds. Also means is provided for supporting the ladle so that it may be easily manipulated and directed into the sprue hole without spilling and also so that when the matrix and sprue hole of the mold are filled the metal will cease to flow and thereby prevent overflow.

20 The invention may be contained in ladles of different forms and which vary in the details of their structures. To illustrate a practical application of the invention, I have selected two of such ladles containing 25 my invention as examples of such structures and shall describe them hereinafter. The structures selected as examples are shown in the accompanying drawings.

30 Figure 1 is a side view showing one form of ladle. Fig. 2 is a view of a section taken on the plane of the line 2—2 indicated in Fig. 1. Fig. 3 is a perspective view of the ladle shown in Fig. 1. Fig. 4 is a view of a vertical section of the ladle when in position to pour the liquid that may be contained therein. Fig. 5 is a view of a section of a modified form of ladle. Fig. 6 is a view of a section taken on the plane of the line 6—6 indicated in Fig. 5. Fig. 7 is an end view of the ladle shown in Fig. 5. Fig. 8 is a side view of one of the ends of the supporting frame of the ladle. Fig. 9 is a perspective view of a sealing channel for closing the mouth of the ladle when in a position intermediate the pouring and filling positions. Fig. 10 is a block having an opening that forms the mouth of the ladle. Fig. 11 is a section through the wall of the ladle, the mouth and the sealing channel, to indicate the relation between the parts shown in Figs. 9 and 10.

50 In the form of construction shown in Figs. 1 to 4, a receptacle for containing the liquid

to be poured is pivotally supported in a 55 frame. The receptacle may be of any suitable form and may be used for pouring liquids of any kind. The supporting frame preferably conforms substantially to the exterior of the lower half of the receptacle. 60 In the particular form of construction shown in the figures, the receptacle is substantially lenticular in form, it having a circular cross section in a plane at right angles to its axis of rotation and the outer edge fits the portion of the supporting frame. The receptacle 1 is segmental in form in that the outer edge portion conforms to $\frac{3}{4}$ of a circle thereby forming an opening which will correspond to about a quadrant of the completed circle, substantially as shown in the figures. The receptacle is provided with the trunnions 2 by means of which the receptacle is pivotally supported on the frame 65 70 75 80 85 90 95

3. The frame 3 has a part 4 that substantially fits the lower half of the outer edge portion of the receptacle 1 and thus when the receptacle 1 is rotated in the support 3 the outer edge of the receptacle 1 slides upon the part 4 of the frame. Preferably the outer edge portion of the receptacle 1 is provided with a ridge 5 that fits a channel 6 that is formed in the part 4 of the frame. The outlet or mouth 7 of the receptacle extends through the ridge 5 and thus the mouth 7 is maintained, during a part of the rotation of the receptacle 1, within the channel 6 and consequently the frame operates to seal or close the mouth 7 during the time that the portion of the ridge 5 lies within the channel 6. The part 4 thus forms a sealing channel for maintaining the mouth closed during the part of the rotation of the receptacle about its axis.

100 The mouth 7 is preferably located substantially in the diameter extending through one of the edges of the receptacle and when this diameter is substantially horizontal the mouth 7 will be located at the top of the frame 3. This will thus constitute the filling position of the receptacle.

When it is desired to pour the liquid from the receptacle it is rotated in the frame 3, the mouth 7 being sealed within the channel 6 until the mouth reaches the bottom of the frame and registers with the opening 8 formed in the frame. The liquid will then

pass out through the mouth 7 and through the opening 8, if desired, into a mold or other receptacle. Thus the liquid will be poured from below its level within the receptacle and all lighter materials such as scum or foreign particles will be separated or segregated from the liquid that passes out through the opening. The ladle is thus particularly useful for pouring of metals as it prevents dross and surface oxidized metal from entering molds.

In order to prevent spilling and overflowing the lower side of the frame 3 has a plane surface 9 that extends over a considerable area and thus the frame may be placed directly on the mold, either a sand or iron mold, and supported thereby. The portion of the mold having the sprue hole may thus be built up to the top of the mold and so that when the frame 3 is placed on the mold the bottom surface 9 of the frame will substantially fit around the sprue hole. If then the frame 3 is so placed that the opening 8 will register with the sprue hole, the molten metal will be poured until the matrix and the sprue hole is filled without spilling and without overflowing, since the metal will discontinue in its flow when the matrix and the sprue hole have been filled.

When the desired quantity of the liquid has been poured the receptacle is turned on its axis. The mouth is immediately closed by the sealing channel of the frame and the frame may be placed in position for pouring the liquid at another point or as may be desired. When the receptacle is turned so that the mouth 7 is located at the top of the frame, it may be cleaned or opened, if plugged or clogged by the metal or material contained within the liquid since it is located above the upper end of the channeled part of the frame and is exposed for such operations as may be found desirable in order to maintain it in operative condition and so that it may perform efficiently its function of delivery of the metal from the receptacle. Preferably the top of the frame and the end where the mouth 7 is located is provided with a trough 10 with which the mouth 7 will register. The other end of the frame cooperates with the stop 11 on the receptacle 1 to prevent further upward movement of the mouth and thus the mouth may be readily caused to register with the end of the trough 10 when the mouth has been raised in the rotation of the receptacle. Also preferably the trough 10 slopes away from the mouth as indicated in the figure. This provides a convenient means for cleaning the mouth and delivery of the material that may be removed in the cleaning operation.

Any suitable means may be used for manipulating the receptacle and handling the frame. In the form of construction

shown in Figures 1 to 4 the receptacle has a handle 12 that may be used for rotating it about its axis and the frame is provided with suitable bars or handles 13 for lifting or shifting the frame.

70

In the form of construction shown in Figs. 5 to 10, the receptacle 15, which corresponds to the receptacle 1 of the other form of construction, is provided with an eye 16 located at its upper end when the mouth is located at the top of the supporting frame. The eye 16 is used when the receptacle 15 contains a relatively large quantity of the liquid that is to be manipulated and provides a means for receiving a hook whereby a suitable crane or other lifting device may be used for handling the receptacle. The receptacle 15 may be rotated in the frame 17 and about the axis of the trunnions 18 by means of the pinion 19 which may be located at one end of the frame 17 and may be operated by a suitable crank or hand wheel such as the hand wheel 20. The pinion 19 meshes with a rack 21 that may be formed in the ridge 22 that forms the outer edge portion of the receptacle 15.

85

In order to protect the metal of the receptacle, particularly at the mouth and that portion of the frame over which the mouth moves between the receptacle filling position and its pouring position, a suitable non-metallic refractory material may be located so as to protect the edge of the receptacle through which the metal is poured and a suitable non-metallic refractory material may be used for covering the sealing channel of the frame. In the form of construction shown in Figs. 5 to 10 a block 23 of non-metallic refractory material or composition of materials is preferably molded to form and fitted into the opening. The block 23 with its opening 24 forms the mouth of a receptacle 15. Also a channel member 25 is shaped to conform to the semi-cylindrical part of the frame 17 and to the ridge 22. It is preferably made to conform to a quarter of a circle over which the mouth will move when it is turned from the non-pouring to the pouring position and consequently the mouth will be closed or sealed by the non-metallic refractory parts as shown in Fig. 11 when the mouth is located in any intermediate position. The lower end of the channel 25 is provided with the opening 26 which is located at the bottom of the frame and through which the metal will be poured when the mouth registers therewith.

95

In order to handle the supporting frame it may be provided with suitable eyes 27 for receiving hooks for shifting the frame by means of a crane or other lifting or moving instrumentality. Particularly when the receptacle 15 is placed in position and the weight of the frame or the combined weight 130

of the filled receptacle and the frame is too great for handling the ladle manually hoisting chains may be connected to the eyes 27.

5 The interior of the receptacle may be lined with clay or coated with a suitable wash according to the character of the metal or liquid that is to be poured into the ladle for the purpose of protecting the material of which the ladle is formed. Where the 10 ladles are used for pouring metals, the interior surfaces are suitably coated with plastic material in the manner well known in the art.

I claim:

15 1. In a ladle, a receptacle having an outlet opening, a member for pivotally supporting the receptacle and for closing the opening of the receptacle, the member having an opening adapted to register with the opening of the receptacle when the receptacle is turned to pouring position.

20 2. In a ladle, a receptacle having an outlet opening, a member for pivotally supporting the receptacle, the member having a sealing arcuate part for closing the opening of the receptacle and an opening adapted to register with the opening of the receptacle when the receptacle has been moved to pouring position.

25 3. In a ladle, a receptacle having an outlet opening, a member for pivotally supporting the receptacle, the member having a sealing arcuate part for closing the opening of the receptacle and an opening located 30 below the pivot point of the receptacle and adapted to register with the opening of the receptacle to permit the escape of the liquid from the receptacle.

35 4. In a ladle, a receptacle having an outlet opening, a member for pivotally supporting the receptacle, the member having a sealing arcuate non-metallic refractory part for closing the opening of the receptacle and an opening adapted to register with the opening of the receptacle when the receptacle has 40 been moved to pouring position.

45 5. In a ladle, a receptacle having an outlet opening, a member for pivotally supporting the receptacle, the receptacle being substantially circular in form in a plane at right angles to its axis of rotation and fitting a portion of the member along the said section, the member adapted to close the opening of the receptacle, the member having an 50 opening adapted to register with the opening of the receptacle when the receptacle has been rotated to a predetermined point about its axis.

55 6. In a ladle, a substantially 270 degree segmental receptacle having an opening, a member for pivotally supporting the receptacle for closing the outlet opening of the receptacle, the member having an opening adapted to register with the opening of the 60

receptacle when the receptacle is turned to 65 pouring position.

7. In a ladle, a receptacle having an outlet opening, a member for pivotally supporting the receptacle, the receptacle being substantially circular in form in a plane at right 70 angles to its axis of rotation and fitting a portion of the member along the said section, the member adapted to close the opening of the receptacle, the member having an opening located below the pivot of the receptacle adapted to register with the opening of the receptacle when the receptacle has been rotated to a predetermined point about 75 its axis.

8. In a ladle, a receptacle having an outlet 80 opening, a frame for pivotally supporting the receptacle, the receptacle being substantially circular in form in a plane at right angles to its axis of rotation, the frame having a non-metallic refractory member fitting 85 the portion of the outer edge of the receptacle and adapted to close the opening of the receptacle, the member having an opening adapted to register with the opening of the receptacle when the receptacle has been rotated to a predetermined point about 90 its axis.

9. In a ladle, a receptacle having an outlet opening, a frame for pivotally supporting the receptacle, the receptacle being substantially circular in form in a plane at right 95 angles to its axis of rotation, the frame having a non-metallic refractory member fitting the portion of the outer edge of the receptacle and adapted to close the opening of the receptacle, the member having an opening adapted to register with the opening of the receptacle when the receptacle has been rotated to a predetermined point about 100 its axis, a frame having a trough adapted to register with the opening of the receptacle and located in the upper end of the member.

10. In a ladle, a receptacle having an outlet opening, a frame for pivotally supporting the receptacle, the receptacle being substantially circular in form in a plane at right angles to its axis of rotation, the frame having a non-metallic refractory member fitting the portion of the outer edge of the receptacle and adapted to close the opening of the receptacle, the member having an opening adapted to register with the opening of the receptacle when the receptacle has been rotated to a predetermined point about 115 its axis, the opening of the receptacle having a refractory block fitting the refractory member, the block having an opening thereto and forming a pouring mouth for the receptacle.

11. In a ladle, a receptacle having an outlet opening, a frame for pivotally supporting the receptacle, the receptacle being substantially circular in form in a plane at 120

right angles to its axis of rotation, a channel member formed of a non-metallic refractory material and fitting a portion of the receptacle, a refractory block having an opening and located in the opening of the receptacle, the said block fitting the inner surfaces of the refractory channel member, the channel

member having an opening adapted to register with the opening of the refractory block when the receptacle has been rotated to a ¹⁰ predetermined point about its axis.

In testimony whereof I have hereunto signed my name to this specification.

JOHN G. KOEGLE.
